(57) **CLAIM**

The ornamental design for an enclosure cover and base for use with AGU fuse blocks, as shown and described.

DESCRIPTION

FIG. 1 is a front perspective view of an enclosure cover and base for use with AGU fuse blocks, showing my new design.

FIG. 2 is a top plan view of FIG. 1;

FIG. 3 is a front side elevation view of FIG. 1;

FIG. 4 is a rear side elevation view of FIG. 1;

FIG. 5 is a bottom plan view of FIG. 1;

FIG. 6 is a left side elevation view of FIG. 5; and,

FIG. 7 is a right side elevation view of FIG. 5.

1 Claim, 3 Drawing Sheets

FIG. 1

FIG. 3**FIG. 2****FIG. 4**

FIG. 6**FIG. 5****FIG. 7**
